ROTARY PUMP AND MOTOR HYDRAULIC
TRANSMISSION SYSTEMWalter Ferris, Milwaukee, Wis., assignor to The
Oilgear Company, Milwaukee, Wis., a corpora-
tion of Wisconsin

Application February 5, 1945, Serial No. 576,243

20 Claims. (Cl. 60—53)

1

This invention relates to hydraulic drives of the type having a hydraulic motor for driving a machine or other apparatus, a pump for supplying motive liquid to the motor to energize it, and a control for varying the relative displacements of the pump and the motor to thereby control the speed of the motor.

A drive embodying the invention is particularly adapted for driving the lighting and air conditioning apparatus of a railway car and it will be explained in connection therewith but it is to be understood that the invention may be employed for other purposes.

The power for driving the lighting and air conditioning apparatus of a railway car is ordinarily derived from the car axle which rotates in one direction or the other at varying speeds in accordance with the direction and speed of the car movement and which moves angularly and vertically in respect to the car body as the car passes around curves and over uneven portions of the track.

A pump ordinarily discharges liquid in a direction and at a rate dependent upon the direction and rate at which it is driven and a hydraulic motor ordinarily operates in a direction and at a speed dependent upon the direction and rate of flow of the liquid which energizes it so that, if the pump were driven from the car axle, the motor would ordinarily operate in opposite directions alternately and at varying speeds but the car lighting and air conditioning apparatus must always be driven in the same direction and at a substantially constant speed.

The present invention has as an object to provide a hydraulic drive including a pump which will deliver liquid in but one direction regardless of the direction in which it is driven.

Another object is to provide a hydraulic drive having a pump which will maintain its displacement at a given maximum at low speeds and will automatically vary its displacement in response to variations in speed above a given speed.

Another object is to provide a hydraulic drive in which a pump and a motor are connected by fluid channels which permit the pump to move relatively to the motor.

Another object is to provide a hydraulic drive having a pump driven at varying speeds, a motor energized by the pump and means for preventing the motor speed from exceeding a predetermined maximum regardless of the pump speed.

Another object is to provide a hydraulic drive including a pump which may be supported from and driven by an axle of a railway car, a hydraulic motor for driving the lighting and air conditioning apparatus of the car, and a control for maintaining the motor speed constant after it reaches a predetermined maximum.

These and other objects and advantages will

60

appear from the description hereinafter given of a hydraulic drive in which the invention is embodied.

According to the invention in its general aspect and as applied to a railway car, the lighting and air conditioning apparatus of the car is driven by a hydraulic motor through an overrunning clutch, the motor is energized by liquid supplied thereto from a reversible variable displacement pump which is supported from and driven by an axle of the car, the reversing mechanism of the pump is operated in response to reversal of car movement so that the pump always delivers liquid in the same direction, the displacement varying mechanism of the pump is operated in response to variations in car speed above an intermediate speed, and the motor speed is maintained constant after it reaches a predetermined maximum.

20 The invention is exemplified by the hydraulic drive shown schematically in the accompanying drawings in which the views are as follows:

Fig. 1 is a side view partly in section of portions of a railway car having a compartment suspended from the car body and its lighting and air conditioning apparatus (not shown) arranged within the compartment according to the usual practice and driven by a hydraulic drive which is constructed according to the invention.

25 Fig. 2 is a plan view taken substantially in the plane indicated by the arrows 2—2 on Fig. 1 but with the truck frame omitted except for small portions thereof adjacent the journal boxes.

30 Fig. 3 is a diagrammatic view illustrating the control for the motor which drives the car lighting and air conditioning apparatus.

35 Fig. 4 is a diagrammatic view illustrating the control for the pump which supplies liquid for energizing the motor shown in Figs. 1 and 3.

40 Fig. 5 is a diagram of the hydraulic circuit.

Since air conditioned railway cars are well known, only so much of the car has been illustrated as is necessary to show the application of the invention thereto. As shown in Fig. 1, the car has a compartment 1 suspended from the car body 2 and enclosing a hydraulic motor 3 which is adapted to drive the car lighting and air conditioning apparatus not shown.

45 The car lighting and air conditioning apparatus is assumed to include an air conditioner, an A. C. motor-generator and a D. C. motor-generator. When the A. C. motor-generator is driven, it supplies current for lighting the car and, when it is energized by current from a source outside the car, it drives the D. C. motor-generator and the air conditioner. When the D. C. motor-generator is driven, it supplies current for charging the car batteries and, when it is energized by current from the batteries, it drives the A. C. motor-generator and the air conditioner. In

3

order that hydraulic motor 3 may drive the car lighting and air conditioning apparatus but not be driven by one or the other of the motor-generators, it is connected thereto through an overrunning clutch 4.

Car body 2 is pivotally supported in the usual manner upon a pair of trucks each of which has a pair of wheels arranged at each end thereof to support the car upon the track but only a portion of one truck has been shown as the car per se 10 forms no part of the present invention.

In the portion shown, a pair of wheels 5 is supported upon a track 6 and fixed upon an axle 7 having opposite ends thereof mounted in a pair of journal boxes 8 which are slidable vertically 15 in opposite sides of the frame 9 of the truck and support car body 2 through springs as is well known.

Hydraulic motor 3 is adapted to be energized by liquid supplied thereto from a reversible variable displacement pump 10 which is arranged beneath the car body 2 and connected to axle 7 by a suitable drive 11 so that pump 10 is driven in one direction or the other in response to movement of the car in one direction or the other.

Pump 10 is fixed to a rigid crossbeam 14 which has a pair of arms 15 fixed to its opposite ends and extending from one side thereof as shown in Figs. 1 and 2. The two arms 15 are connected, respectively, to two lugs 16 which are welded or otherwise rigidly secured, respectively, to the two journal boxes 8 and support crossbeam 14 at one side thereof. The other side of crossbeam 14 may be suspended by a hanger which is connected directly thereto but, with the type of pump shown, it is preferably connected to a housing 17 which encloses the control mechanism for pump 10. Housing 17 is fixed to or formed integral with a housing 18 which encloses pump 10 and is fixed to crossbeam 14 so that housings 17 and 18 and crossbeam 14 form a rigid support for pump 10.

As shown in Figs. 1 and 2, the hanger for the pump support may include a curved track such as an I-beam 19 which is fixed by an upper flange to the center sill 20 of the car body, a trolley 21 which is mounted upon the lower flange of track 19 and a link 22 which is pivotally connected to trolley 21 and to suitable lugs 23 fixed to housing 17 from the centerline of the pump support.

When the car passes around a curve, the truck will pivot beneath the car body and trolley 21 will move along the track 19 so that hanger 21-22 remains substantially vertical at all times. In order to prevent the pump support from dropping upon track 6 in case hanger 21-22 should fail, a link 24 has its lower end pivoted to housing 18 and its upper end slotted to receive a pin 25 carried by truck frame 9.

Since the car body is supported upon springs, it will move vertically relative to axle 7 and it will sway and lurch due to curves and to unevenness of the track. Swaying and lurching of the car body will not cause any lateral or tilting movement of the pump support for the reason that hanger 21-22 is connected to the pump support upon the centerline thereof. Vertical movements of the car body, however, will be transmitted to the pump support through hanger 21-22, and in order that the pump support may pivot relatively to axle 7 and to permit adjustment of drive 11, the two arms 15 are pivotally connected, respectively, to the two lugs 16 by two eccentric pins 26 each of which has attached thereto a lever 27 by means of which it may be rotated to move the pump support toward or from axle 7.

4

The arrangement is such that the pump support may pivot upon pins 26 in response to vertical movements of car body 2 relative to axle 7 while eccentric pins 26 positively retain the pump support in parallelism with axle 7 and, since hanger 21-22 is connected to the pump support at a single point upon the centerline thereof and its upper end is movable transversely of car body 2 so that the pump support cannot be moved laterally or tilted by movement of car body 2, no material distortion of drive 11 will occur.

In order that drive 11 may be properly lubricated and be protected from dust and other foreign matter, it is preferably enclosed within a suitable enclosure including a housing 28, which is rotatably supported upon axle 7, and a flexible and extensible shield 29 which connects housing 28 to pump housing 18, rotation of housing 28 being prevented by a link 30 which connects it to crossbeam 14.

The enclosure for drive 11 and the arrangement for supporting pump 10 do not per se form any part of the present invention but are fully disclosed and claimed in my co-pending application Serial No. 576,242 filed February 5, 1945 to which reference may be had for details of construction.

Motor 3 and pump 10 are preferably of the sliding vane type for the reason that a hydrodynamic machine of that type has a greater volumetric capacity per unit of weight than a piston type machine. In a pump of the sliding vane type, a major volume of liquid is displaced by the outer end portions of the vanes and a minor volume of liquid is displaced by the inner ends of the vanes. In the present instance, the major volume is employed to drive motor 3 and the minor volume is employed principally to hold the motor vanes against the vane track of motor 3 so that two separate circuits are required.

Each side of each circuit must include a flexible portion for the reason that pump 10 moves relatively to motor 3 when the car is in motion. Each flexible portion may comprise a length of flexible hose but for the purpose of illustration the circuits have been shown as including two slide pipes 35 and 36 having one end of each connected to pump housing 18 and the other end of each connected to a manifold 37 which is fixed to car body 2 and connected to motor 3 by four fluid channels 38, 39, 49 and 41.

The liquid in slide pipes 35 and 36 exerts forces which tend to move pump housing 18 and manifold 37 away from each other and those forces are counterbalanced at least in part by a hold-up mechanism comprising a cylinder 42, which is fixed to pump housing 18, and a rod 43 which is connected by universal joints to manifold 37 and to a piston (not shown) which is fitted in cylinder 42 and continuously subjected to pump pressure.

Slide pipes 35 and 36 and hold-up mechanism 42-43 have not been shown in detail as they are fully illustrated and described in the above mentioned application to which reference may be had for the specific construction thereof. Slide pipes 35 and 36 are specifically claimed in Patent No. 2,462,734.

It is deemed sufficient to state herein that slide pipes 35 and 36 are extensible and contractible in length, that each is bendable at two points and that each contains a high pressure channel and a low pressure channel.

As shown schematically in Fig. 5, slide pipe 35 contains a large capacity high pressure channel 44, which communicates through manifold 37 with channel 38 on car body 2, and a smaller

capacity low pressure channel 45 which communicates through manifold 37 with channel 39 on car body 2. Slide pipe 36 contains a small capacity high pressure channel 46, which communicates through manifold 37 with channel 40 on car body 2, and a larger capacity low pressure channel 47 which communicates through manifold 37 with channel 41 on car body 2.

The arrangement is such that the liquid for driving motor 3 flows through channels 44 and 38, the liquid discharged by motor 43 flows through channels 41 and 47, the liquid discharged by the inner ends of the pump vanes flows through channels 46 and 40, and the liquid discharged by the inner ends of the motor vanes flows through channels 39 and 45.

Pump 10 has its rotor 50 (Fig. 4) fixed upon a shaft 51 to which drive 11 (Fig. 1) is connected so that rotor 50 is rotated at varying speeds in one direction or the other in response to movement of the car at varying speeds in one direction or the other.

Pump 10 has been shown as being of the type illustrated and described in application Serial No. 537,346 filed May 25, 1944 to which reference may be had for specific details of construction. It is deemed sufficient to state herein that rotor 50 is arranged within a spacer ring 52 and provided with a plurality of radial vane slots 53 each of which has a vane 54 slidably fitted therein. During rotation of rotor 50, the outer ends of vanes 54 ride upon a vane track which is approximately elliptical when the pump is functioning. The vane track is formed by two diametrically opposed bridges 55, two bridges 56 which are spaced 90° from bridges 55, and four extensible vane track sections 57 each of which is arranged between adjacent bridges and pivotally connected thereto.

The space between the vane track and the periphery of rotor 50 communicates through track sections 57 with two diametrically opposed low pressure or intake ports 58 and with two diametrically opposed high pressure or discharge ports 59 each of which is formed in spacer ring 52 between adjacent bridges.

Spacer ring 52 is tightly clamped between two cheek plates (not shown) one of which has openings extending therethrough from ports 58 and 59 into communication with fluid channels which are formed in pump housing 18 and lead to the inlet and outlet ports of pump 10. As shown schematically in Fig. 5, both low pressure ports 58 communicate with a channel 60 to which channel 47 in slide pipe 36 is connected, and both high pressure ports 59 communicate with a channel 61 to which channel 44 in slide pipe 35 is connected.

The inner ends of vane slots 53 in rotor 50 (Fig. 4) register selectively with vane slot ports which are formed in the inner face of a cheek plate and communicate through the cheek plate with fluid channels formed in pump housing 18 and constituting parts of the vane root circuit. As shown schematically in Fig. 5, channel 45 in slide pipe 35 communicates with a channel 62 which leads to two diametrically opposed vane slot ports 63 which are formed in the inner face of a cheek plate inward from ports 58, and channel 46 in slide pipe 36 communicates with a channel 64 which leads to two diametrically opposed vane slot ports 65 which are formed in the inner face of the cheek plate inward from ports 59.

The outer portions of bridges 55 and 56 are arranged, respectively, in recesses 68 and 69 (Fig. 4) which are formed in spacer ring 52. The outer portion of each bridge is closely fitted in a recess

and closely fitted between the cheek plates so that the outer portion of the bridge functions as the piston and the recess functions as the cylinder of a servomotor for moving the bridge inward and for controlling the outward movement thereof, each bridge being constantly urged outward by springs (not shown) and also being urged outward by forces exerted upon the vane track by the liquid when the pump is creating pressure.

Bridges 55 and 56 are adapted to be moved inward or permitted to move outward by liquid delivered to or permitted to escape from their recesses under the control of two follow-up type pilot valves 70 and two follow-up type pilot valves 71 which are fitted, respectively, in bridges 55 and 56 and of which only the stems have been shown.

The arrangement is such that, when the pilot valve of a bridge is moved inward, liquid will enter the recess in which that bridge is fitted and will move that bridge inward the same distance that the pilot valve was moved inward and then that bridge will cut off further flow of liquid to the recess and movement of the bridge will cease. When the pilot valve of a bridge is moved outward, liquid will escape from the recess in which that bridge is fitted and will permit that bridge to move outward the same distance that its pilot valve was moved outward and then that bridge will cut off further escape of liquid from the recess and movement of the bridge will cease.

Pilot valves 70 and 71 are operated by a cam ring 72 which extends around spacer ring 52 and has two diametrically opposed cam grooves 73 and two diametrically opposed cam grooves 74 formed in its inner peripheral surface. Cam grooves 73 are located at such angular distances from cam grooves 74 that, when cam ring 72 is in its neutral position, each pilot valve stem engages a concentric portion of cam ring 72 at the end of a cam groove so that a slight rotation of cam ring 72 from its neutral position in one direction permits the stems of pilot valves 70 to move outward along cam grooves 73 and a slight rotation of cam ring 72 from its neutral position in the opposite direction permits the stems of pilot valves 71 to move outward along cam grooves 74. Cam ring 72 is adapted to be rotated by mechanism to be presently described.

Liquid for operating bridges 55 and 56 when pump pressure is low or absent and for keeping both the main circuit and the vane root circuit flooded is supplied by a gear pump 75 which is driven in unison with the main pump and arranged in the casing thereof. In the present instance, rotor 50 of the main pump is driven in one direction or the other in response to movement of the car in one direction or the other so that gear pump 75 is also driven in opposite directions alternately but it must deliver liquid in only one direction.

As shown schematically in Fig. 5, gear pump 75 has its opposite sides connected to two channels 76 and 77 adjacent ends of which are connected, respectively, through two check valves 78 and 79 to a channel 80 extending into a reservoir 81 which may be arranged within crossbeam 14. Check valves 78 and 79 permit pump 75 to draw liquid from reservoir 81 into either channel 76 or channel 77 but prevent pump 75 from discharging liquid into reservoir 81.

The other ends of channels 76 and 77 are connected, respectively, through two check valves 82 and 83 to a branched channel 84 which has one branch thereof connected to channel 62 and an-

other branch thereof connected to pilot valves 10 and 71 through channels not shown. Check valves 82 and 83 permit gear pump 75 to discharge liquid through either channel 76 or channel 77 into channel 84 but prevent flow of liquid from one to the other of channels 76 and 77.

The arrangement is such that, when gear pump 75 is driven in one direction, it will draw liquid from reservoir 81 through channel 80, check valve 78 and channel 76 and discharge it through channel 77 and check valve 83 into channel 84 and, when gear pump 75 is driven in the opposite direction, it will draw liquid from reservoir 81 through channel 80, check valve 79 and channel 77 and discharge it through channel 76 and check valve 82 into channel 84.

A part of the liquid discharged by gear pump 75 into channel 84 flows to channel 62 to keep the vane root circuit flooded, another part flows when needed to pilot valves 70 and 71 to effect operation of bridges 55 and 56, and the remainder of the liquid discharged by gear pump 75 flows through a resistance valve 85 into a channel 86 which is connected to channel 60. A part of the liquid discharged into channel 86 flows into channel 60 to keep the main circuit flooded and the remainder of the liquid is exhausted through a relief valve 87 and a channel 88 into reservoir 81. Gear pump 75 thus maintains in the return side of the main circuit a pressure equal to resistance of valve 87 and it maintains in the return side of the vane root circuit and in channel 84 a pressure equal to the sum of the resistances of valves 85 and 87. The pressure in channel 84 is sufficient to operate bridges 55 and 56 until it is exceeded by the pressure created by pump 10 and then bridges 55 and 56 are operated by liquid supplied by pump 10 as explained in application Serial No. 537,346.

When bridges 55 and 56 are in the positions shown in Fig. 4 and rotor 50 is rotated in a clockwise direction, the vanes will move outward as they travel from inward bridges 56 to outward bridges 55. The spaces between the outer portions of the outward moving vanes will be filled with liquid from intake ports 58 and this liquid will be expelled into discharge ports 59 as the vanes travel from outward bridges 55 to inward bridges 56 and are forced inward by the vane track. Pump 10 will thus discharge liquid at the maximum rate at that particular speed of rotor 50 for the reason that bridges 56 are in their innermost positions with the track surfaces thereon close to the periphery of rotor 50 and bridges 55 are in their outermost positions with the track surfaces thereon spaced the maximum distance from the periphery of rotor 50 so that pump displacement is maximum. The outward moving vanes are held in contact with the vane track by the pressure maintained in vane slot ports 63 by gear pump 75 and the inward moving vanes will expel liquid from their slots into vane slot ports 65.

If cam ring 72 is rotated in a clockwise direction from the position shown in Fig. 4, pilot valves 70 will be pushed inward by cam grooves 73 and cause bridges 55 to move inward, thereby decreasing pump displacement and consequently decreasing the rate of pump delivery at any given speed. During continued rotation of cam ring 72, bridges 55 will continue to move inward until cam ring 72 reaches its neutral position and then all four bridges will be in their innermost positions so that pump displacement is zero. Rotation of cam ring 72 beyond its neutral position

will permit the stems of pilot valves 71 to move outward along cam grooves 74 and cause bridges 56 to move outward, thereby reversing the pump.

If rotor 50 continued to rotate in the same direction after bridges 56 were moved outward, pump 10 would discharge in the opposite direction but in the present instance the pump is reversed only in response to reversal of the direction of rotation of rotor 50 so that pump 10 always delivers liquid in the same direction. That is, bridges 55 are moved outward only when rotor 50 is driven in a clockwise direction and bridges 56 are moved outward only when rotor 50 is driven in a counterclockwise direction so that pump 10 always discharges liquid through its discharge ports 59.

Cam ring 72 is adapted to be rotated in one direction or the other by a control which is arranged within control housing 17 (Fig. 1) and is shown schematically in Fig. 4. The control includes two flow responsive devices 91 and 91^a one or the other of which is first operated and effects rotation of cam ring 72 to one or the other of its maximum displacement positions in response to pump 10 being driven in one direction or the other and the previously unoperated device will thereafter rotate cam ring 72 in a direction to reduce pump displacement in response to pump 10 being driven at speeds above an intermediate speed.

Device 91 includes a plunger 92 which is fitted in a stationary cylinder 93 and has a piston 94 fixed to or formed thereon and fitted in a counterbore 95 formed in the body of cylinder 93 concentric with the bore thereof. Plunger 92 is urged inward and normally held against the head end of cylinder 93 by a spring 96 arranged between its outer end and a stationary abutment 97. Plunger 92 is adapted to be moved outward by liquid delivered to the head end of cylinder 93 as will presently be explained, outward movement of plunger 92 being limited by a stop 98 which is fixed to cylinder 93 and adapted to be engaged by piston 94.

Cylinder 93 has an annular groove or port 99 formed in the wall of its bore at its inner end, an annular groove or port 100 formed in the wall of its bore and spaced from port 99, and an annular groove or port 101 formed in the wall of counterbore 95 at the inner end thereof. Communication between ports 99 and 100 is provided by a plurality of tapered grooves 102 which are formed in the peripheral surface of plunger 92 at the inner end thereof and permit restricted flow from port 99 to port 100. Communication between port 99 and port 101 is provided by a passage 103 which extends axially into plunger 92 from the inner end thereof and then extends radially outward at such a point that it registers with port 101 when plunger 92 is in its outermost position.

Device 91^a is substantially the same as device 91 and a description thereof is deemed unnecessary since like parts have been indicated by like reference numerals with the exponent "a" added to the reference numerals applied to device 91^a.

In order that cam ring 72 may be adjusted by one and the adjustment modified by the other of devices 91 and 91^a, a floating lever 104 has its ends rounded and fitted in two slots 104 and 105^a formed in the outer portions of plungers 92 and 92^a respectively. Lever 104 is pivotally connected at its center to one end of a link 106 which has its other end pivoted to cam ring 72. The arrangement is such that, when one of the two

plungers such as plunger 92 is moved outward to the limit of its movement, lever 104 will pivot in the slot in the other plunger and cause link 106 to rotate cam ring 72 in one direction to a maximum displacement position and then, when the other plunger such as plunger 92^a is moved outward a limited distance, lever 104 will pivot in the slot of the first plunger and cause link 106 to rotate cam ring 72 a limited distance in the opposite direction and thereby reduce pump displacement.

Liquid for operating flow responsive devices 91 and 91^a is supplied by a gear pump 110 which is driven in unison with pump 10 and arranged in the casing thereof. Since pump 10 is driven in one direction or the other at varying speeds in response to car movement in one direction or the other at varying speeds, pump 10 will be driven at varying speeds in opposite directions alternately and it will discharge liquid in a direction corresponding to the direction of car movement and at a rate proportional to car speed.

Gear pump 110 has its opposite sides connected to two channels 111 and 112 the lower ends of which are connected, respectively, through two check valves 113 and 114 to a channel 115 which extends into reservoir 81. Check valves 113 and 114 permit gear pump 110 to draw liquid from reservoir 81 into either channel 111 or channel 112 but prevent gear pump 110 from discharging into reservoir 81.

Flow of liquid from gear pump 110 to devices 91 and 91^a is controlled by a valve 116 which is fitted in the bore of valve casing 117 having five annular grooves or ports 118, 119, 119^a, 120 and 120^a formed in the wall of its bore and channels 111 and 112 connected, respectively, to opposite ends of its bore. Valve casing 117 is symmetrical about its transverse centerline and port 118 is located upon the centerline and communicates with a channel 121 which discharges into reservoir 81.

Ports 119 and 119^a are arranged at opposite sides of port 118 and are connected, respectively, by channels 122 and 122^a to ports 100 and 100^a in devices 91 and 91^a respectively. Ports 120 and 120^a are spaced from ports 119 and 119^a, respectively, and are connected to ports 99 and 99^a in devices 91 and 91^a by channels 123 and 123^a respectively. Port 101 in device 91 is connected to channel 123^a at a point intermediate the ends thereof by channel 124 having a check valve 125 arranged therein. Port 101^a in device 91^a is connected to channel 123 at a point intermediate the ends thereof by a channel 124^a having a check valve 125^a arranged therein.

When gear pump 110 is rotated in one direction, it will draw liquid from reservoir 81 through channel 115, check valve 114 and channel 112 and discharge it into channel 111. Since check valve 113 prevents the liquid from being discharged into reservoir 81, the liquid will flow to the end of valve casing 117, move valve 116 downward in respect to the drawing and then flow through channel 123 to port 99 and advance plunger 92 for the reason that check valve 125^a prevents the liquid from flowing through channel 124^a. Advancing plunger 92 opens passage 103 to port 101 and then the liquid will flow therethrough and through channels 124 and 123^a, port 99^a, grooves 102^a, port 100^a, channel 122^a, valve casing 117 and channel 121 to reservoir 81 and effect operation of device 91^a in response to the car reaching a predetermined speed as will presently be explained.

When gear pump 110 is rotated in the opposite

direction, it will draw liquid from reservoir 81 through channel 115, check valve 113 and channel 111 and discharge it into channel 112. Since check valve 114 prevents the liquid from being discharged into reservoir 81, the liquid will flow to the end of valve casing 117, move valve 116 upward in respect to the drawing and then flow through channel 123^a to port 99^a and advance plunger 92^a for the reason that check valve 125 prevents liquid from flowing through channel 124. Advancing plunger 92^a opens passage 103^a to port 101^a and then the liquid will flow therethrough and through channels 124^a and 123, port 99, grooves 102, port 100, channel 122, valve casing 117 and channel 121 to reservoir 81 and effect operation of device 91 in response to the car reaching a predetermined speed as will presently be explained.

Motor 3 may be a constant displacement motor and its speed may be maintained substantially constant by varying the displacement of pump 10 inversely to the variations in car speed above an intermediate speed. However, a constant displacement motor just large enough to drive the car lighting and air conditioning apparatus when supplied with liquid at a maximum pressure would have to operate at that maximum pressure during the entire time it was driving the car lighting and air conditioning apparatus. Also, a constant displacement motor large enough to drive the car lighting and air conditioning apparatus when supplied with liquid at a lower pressure would require a larger pump in order to maintain motor speeds substantially constant at all car speeds above an intermediate speed by varying the displacement of pump inversely to variations in car speed above that intermediate speed.

It is therefore desirable to employ a variable displacement motor which will drive the car lighting and air conditioning apparatus when motor displacement is considerably less than maximum and which will automatically increase its displacement when the car is running at high speeds so that the pump and the motor will operate at high pressures for only short intervals and will operate at lower pressures during the greater part of the time that the motor is driving the car lighting and air conditioning apparatus.

For the purpose of illustration, motor 3 has been shown as having an internal construction substantially the same as that of pump 10 except that its bridges are not operated hydraulically under the control of pilot valves as in pump 10. Therefore, corresponding parts have been indicated by corresponding reference numerals with the exponent "a" added to the reference numerals applied to motor 3 and only a brief description is deemed necessary.

As shown in Fig. 3, motor 3 has its rotor 50^a fixed upon a shaft 131 which, as indicated in Fig. 1, is connected through clutch 4 to the car lighting and air conditioning apparatus. Rotor 50^a is arranged within a spacer ring 52^a and provided with a plurality of radial vane slots 53^a each of which has a vane 54^a slidably fitted therein. The outer ends of vanes 54^a engage a substantially elliptical vane track formed by two diametrically opposed movable bridges 55^a, two stationary bridges 56^a which are spaced 90° from bridges 55^a, and four extensible vane track sections 57^a each of which is arranged between adjacent bridges and pivotally connected thereto.

Two diametrically opposed inlet ports 58^a and two diametrically opposed outlet ports 59^a are formed in spacer ring 52^a which is clamped be-

11

tween two cheek plates not shown. As shown schematically in Fig. 5, both inlet ports 58^a communicate through openings in one of the cheek plates with a fluid channel 60^a which is formed in the motor housing and has channel 38 connected thereto, and both outlet ports 59^a communicate through openings in one of the cheek plates with a fluid channel 61^a which is formed in the motor housing and has channel 41 connected thereto.

The inner ends of vane slots 53^a register selectively with two diametrically opposed vane slot ports 63^a and two diametrically opposed vane slot ports 65^a which are formed in the inner face of a cheek plate inward from ports 58^a and 59^a respectively. Ports 63^a are both connected to channel 40 by a channel 62^a formed in the motor housing, and ports 65^a are both connected to channel 39 by a channel 64^a formed in the motor housing.

Bridges 55^a (Fig. 3) have the outer portions thereof slidably fitted in recesses 68^a which are formed in spacer ring 52^a but bridges 56^a are rigidly secured in spacer ring 52^a instead of being slidable therein as are bridges 56 of pump 10. The outer portions of bridges 55^a are closely fitted between the two cheek plates and in recesses 68^a and form therewith substantially fluid tight slideable joints to prevent leakage of liquid from the interior of the motor. Instead of bridges 55^a being moved inward and outward in response to liquid flowing to and from their recesses under the control of pilot valves as in pump 10, they are adapted to be moved outward by the pressure of the motive liquid acting upon the inner faces thereof and they are adapted to be moved inward mechanically by mechanism to be presently described, the outer ends of recesses 68^a being drained to prevent entrapment of air and leakage liquid.

Motor 3 thus has an internal construction similar to that of pump 10 except for the means for operating the bridges but it functions oppositely to pump 10. That is, liquid discharged by pump 10 flows through channels 61, 44, 38 and 60^a and ports 58^a, across the faces of bridges 55^a and through ports 59^a and channels 61^a, 41, 47 and 60 to intake ports 58 of pump 10. The vanes in contact with bridges 55^a are carried thereacross by the liquid and cause rotor 50^a to rotate and moves succeeding vanes into contact with bridges 55^a so that rotor 50^a is rotated continuously and drives shaft 131 at a speed determined both by the rate at which liquid is delivered to motor 3 and by the displacement of motor 3.

Vanес 54^a must move outward as the outer ends thereof travel from a bridge 56^a to a bridge 55^a and they are forced inward as the outer ends thereof travel from a bridge 55^a to a bridge 56^a. The liquid expelled by the inward moving pump vanes 54 from their slots into vane slot ports 65 flows therefrom through channels 64, 46, 40 and 62^a and vane slot ports 63^a into the slots of the outward moving motor vanes 54^a and holds those vanes in contact with the vane track, and the inward moving motor vanes 54^a eject liquid from their slots through ports 65^a, passages 64^a, 39, 45 and 62 and vane slot ports 63 into the slots of the outward moving pump vanes 54.

Since the outer ends of the outward moving motor vanes 54^a are subjected to pump pressure, the inner ends thereof must be subjected to a higher pressure in order to move the vanes outward and positively hold the outer ends thereof in contact with the vane track. This is accomplished by providing a pump having a total

12

vane displacement greater than the total vane displacement of the motor such as by making pump vanes 54 slightly thicker than motor vanes 54^a. The volume of liquid pumped by the inner ends of the pump vanes is thus in excess of the volume required to move the motor vanes outward and the excess is exhausted from the high pressure side of the vane root circuit into the high pressure side of the main circuit such as by connecting a resistance valve 132 between channels 64 and 61 so that the inner ends of the outward moving motor vanes are subjected to a pressure which exceeds the pressure to which the outer ends thereof are subjected by an amount equal to the resistance of valve 132. The pressure in the main circuit is limited to a predetermined maximum such as by connecting a relief valve 133 between channels 60 and 61.

Motor 3 is provided with a control which will maintain the motor speed substantially constant after it reaches a predetermined maximum, such as the control shown schematically in Fig. 3. That control includes two push rods 140 and 141 each of which engages the outer end of a bridge 55^a and is slidably fitted in spacer ring 52^a and in a wall of the motor housing.

The outer end of push rod 140 engages the lower end of a lever 142 which is pivoted intermediate its ends upon a shaft 143 carried by the motor housing, and the outer end of push rod 141 engages an intermediate portion of a lever 144 which is pivoted at its lower end upon a shaft 145 carried by the motor housing so that moving the upper ends of both levers toward the right causes both of bridges 55^a to be moved inward and moving the upper ends of both levers toward the left permits both of bridges 55^a to be moved outward by pressure acting upon the inner faces thereof.

The upper ends of levers 142 and 144 are connected, respectively, by two links 146 and 147 to two piston rods 148 and 149 fixed to opposite ends of a piston 150 which is fitted in a stationary cylinder 151 and urged toward the right by a spring 152 having sufficient strength to effect inward movement of bridges 55^a when the pressure within motor 3 is very low. Piston 150 is also adapted to be moved toward the right by liquid supplied to cylinder 151 through a channel 153 from the high pressure side of the main circuit. Piston 150 and levers 142 and 144 are so proportioned that, when cylinder 151 is supplied with liquid, piston 150 and spring 152 will move bridges 55^a inward against the forces exerted upon the inner faces thereof by the liquid within motor 3.

Inward movement of bridges 55^a is limited by a stop screw 154 which engages lever 142 and is adjusted to stop further inward movement of bridges 55^a when motor displacement has been reduced to a predetermined minimum, such as one half of maximum displacement. Outward movement of bridges 55^a is limited by a stop screw 155 which engages lever 144 and is adjusted to stop further outward movement of bridges 55^a when motor displacement has been increased to a predetermined maximum, such as full displacement.

Liquid flows through channel 153 to and from cylinder 151 under the control of a pilot valve 160 having three spaced apart heads or pistons 161, 162 and 163 fixed or formed thereon and closely fitted in the bore of the valve casing 164. Piston 161 controls communication between channel 153, which is connected to valve casing 164 at or near the center thereof, and a channel 165

which has one end connected to valve casing 164 at a point between pistons 161 and 162 and its other end connected to the high pressure side of the main circuit such as by being connected to passage 60^a as shown in Fig. 5. Piston 161 also controls communication between channel 153 and a drain channel 166 which is connected to valve casing 164 at a point between pistons 161 and 163 and discharges into the housing of motor 3. Liquid discharged or leaking into the 10 housing of motor 3 is drained into reservoir 81 through channels not shown.

Pilot valve 160 is controlled by a speed responsive device which may be of the type shown schematically in Fig. 3 and which may be enclosed with the pilot valve within a housing 167 arranged upon the housing of motor 3 as shown in Fig. 1. The speed responsive device chosen for illustration includes a floating lever 168 which has one end pivoted to the stem of pilot valve 160 and its other end connected by a pin and slot connection to the case 169^a of a differential 169. Lever 168 is pivotally connected intermediate its ends to one end of a follow-up rod 170 which is slidable in suitable guides and has its lower end urged by a spring 171 against a cam 172 fixed to or formed upon piston rod 149.

Differential 169 has not been illustrated in detail as it is a well known three legged type. It is deemed sufficient to state herein that differential case 169^a is mounted for rotation upon adjacent end portions of two shafts 169^b and 169^c which are journaled in suitable bearings and constitute the first and second legs of the differential. Case 169^a, which constitutes the third leg of the differential, encloses a gear mechanism for transmitting motion from either shaft to the case. For the purpose of this explanation, it will be assumed that the gear mechanism is such that case 169^a will remain stationary when shafts 169^b and 169^c are driven at the same speed but will rotate in response to one shaft rotating through a greater angular distance than the other shaft.

Shaft 169^b is driven from motor shaft 131 through a suitable drive 173 and shaft 169^c is driven through reduction gears 174 and 175 and a slipping clutch 176 by a small constant speed electric motor 177. Drive 173 and gears 174 and 175 are so proportioned that, when motor 3 is operated at the correct speed for driving the car lighting and air conditioning apparatus, shafts 169^b and 169^c will be driven at the same speed and differential case 169^a will remain stationary and hold pilot valve 160 in such a position that piston 161 blocks the end of channel 153 so that liquid cannot flow to or from cylinder 151 to effect a change in the displacement of motor 3.

Motor 3 does not operate fast enough to drive the car lighting and air conditioning apparatus at the proper speed until the car reaches an intermediate speed but electric motor 177 operates continuously at a substantially constant speed and tends to keep differential case 169^a rotating whenever the speed of motor 3 is too low. In order to prevent differential case 169^a from being rotated a material angular distance beyond its operating range, rotation thereof is prevented by suitable stops and slipping clutch 176 is provided.

As shown, an abutment 178 fixed to differential case 169^a is adapted to engage a stop screw 179 just as or just after case 169^a reaches one end of its operating range, and if desired, a second abutment 180 may be provided to engage a second stop screw (not shown) just as or just after

the differential case reaches the other end of its operating range.

The arrangement is such that, when the car is stationary so that motor 3 is idle and is preventing rotation of shaft 169^b, energizing electric motor 177 will cause it to drive differential 169 until abutment 178 engages stop screw 179 and then clutch 176 will slip and permit motor 177 to operate without driving differential 169.

Operation

When the car is stopped temporarily at a station, pump 10 and motor 3 will be idle and the car lighting and air conditioning apparatus will be driven by the D. C. motor-generator. When the car starts to move in one direction or the other, pump 10 will be driven in one direction or the other but it will deliver liquid in only one direction regardless of the direction in which it is driven and the liquid discharged by pump 10 will flow through channels 61, 44, 38 and 60^a and cause motor 3 to operate in a clockwise direction as previously explained, the liquid discharged by motor 3 being returned through channels 61^a, 41, 47 and 60 to pump 10.

Motor 3 will drive shaft 131 but the D. C. motor-generator will continue to drive the car lighting and air conditioning apparatus for the reason that pump 10 even at maximum displacement cannot deliver enough liquid to cause motor 3 to operate fast enough to drive the car lighting and air conditioning apparatus at the correct speed until the car has accelerated to a predetermined intermediate speed, such as 25 M. P. H.

It has previously been explained that the flow control mechanism shown in Fig. 4 causes pump 10 to discharge liquid in one direction only regardless of the direction of car movement. Since the two halves of the flow control mechanism are identical and function in exactly the same manner, it is believed that an explanation of the operation of the drive during movement of the car in one direction will suffice.

Assuming that the car moves in a direction to cause pump 10 to be driven in a clockwise direction in respect to Fig. 4, gear pump 110 will be driven in the same direction and the liquid discharged thereby will flow through channel 111, valve casing 117 and channel 123 to cylinder 93 and move plunger 92 downward against the resistance of spring 96 until passage 103 opens to port 101 so that the liquid can then flow through channel 124 into channel 123^a. Since port 120^a is at this time blocked by valve 116, the liquid entering channel 123^a will flow therethrough and through grooves 102^a, channel 122^a, valve casing 117 and channel 121 to reservoir 81. Plunger 92 in moving downward will carry the left end of lever 104 with it and cause link 106 to rotate cam ring 72 counterclockwise until the displacement of pump 10 is substantially maximum as previously explained.

Since pumps 10 and 110 are driven from an axle of the car, the speeds thereof will be proportional to the speed of the car. Therefore, the rate at which pump 10 delivers liquid will increase with and be proportional to the car speed as long as its displacement remains constant, and the rate at which pump 110 delivers liquid will increase with and be proportional at all times to the car speed for the reason that pump 110 has a constant displacement.

When plunger 92^a is in its innermost position, the effective area of grooves 102^a are large enough to pass the entire volume of liquid discharged by

pump 110 without causing the pressure therein to become high enough to raise plunger 92^a against the resistance of spring 96^a until the car reaches a predetermined intermediate speed, such as 25 M. P. H.

As the car speed increases above the intermediate speed, the output of pump 110 correspondingly increases and causes pressure to rise sufficiently to move plunger 92^a upward and thereby increase the effective areas of grooves 102^a sufficiently to accommodate the increased flow of liquid. Plunger 92^a in moving upward will carry the right end of lever 104 with it and thereby cause link 106 to rotate cam 72 clockwise to reduce the displacement of pump 10.

If a constant displacement motor is employed to drive the car lighting and air conditioning apparatus, grooves 102^a are of such size and have such a taper that the liquid flowing therethrough at car speeds above the intermediate speed causes plunger 92^a to rise and reduce the displacement of pump 10 in proportion to the increase in car speed so as to maintain the output of pump 10 substantially constant and thereby maintain the motor speed substantially constant.

If a variable displacement motor is employed as shown, grooves 102^a are of such size and have such a taper that liquid flowing therethrough at car speeds above the intermediate speed causes plunger 92^a to rise and reduce the displacement of pump 10 at a rate less than the rate of car acceleration and the speed of the motor is maintained substantially constant by varying motor displacement in response to the motor speed tending to vary from the correct speed.

In the drive chosen for illustration, the parts have been shown in the positions occupied when the car is running at a speed less than the predetermined intermediate speed. As shown, flow control device 91 has adjusted pump 10 to maximum displacement, pump 10 is delivering liquid to motor 3 which is operating at a speed less than the correct speed for driving the car lighting and air conditioning apparatus, spring 152 is maintaining the displacement of motor 3 at the predetermined minimum, motor 3 is driving shaft 169^b at slow speed, electric motor 177 is driving shaft 169^c and tending to drive it faster than shaft 169^b so that abutment 178 is held against stop screw 179, and clutch 176 is slipping to permit motor 177 to operate at full speed.

As the car speed increases, the output of pump 10 and consequently the speed of motor 3 will increase proportionally until at the intermediate speed motor 3 will run fast enough to pick up the load through overrunning clutch 4. Picking up the load will cause pump pressure to rise enough to enable motor 3 to drive the car lighting and air conditioning apparatus and this pressure will extend through channel 165, pilot valve casing 164 and channel 153 to cylinder 151 and enable piston 150 to prevent bridges 55^a from being moved outward by the pressure acting upon the inner faces thereof.

After the car reaches the intermediate speed, pump 10 will continue to deliver liquid to motor 3 at a rate in excess of the rate required to drive it at the correct speed. Motor 3 will therefore tend to accelerate and it will rotate shaft 169^b through a greater angular distance than shaft 169^c is being rotated by constant speed motor 177, thereby causing differential case 169^a to rotate a limited angular distance counterclockwise and to move the right end of lever 168 downward.

Lever 168 will pivot upon follow-up rod 170 and raise pilot valve 160 until piston 161 thereon first blocks the end of channel 153 and then opens a small lower portion thereof to drain channel 166 to permit liquid to escape from cylinder 151 so that the pressure within motor 3 may move bridges 55^a outward to increase the motor displacement and thereby prevent the motor speed from increasing beyond the correct speed as determined by constant speed motor 177.

Bridges 55^a in moving outward will swing levers 142 and 144 upon shafts 143 and 145 respectively, the upper ends of the levers will move piston 150 toward the left, piston 150 will eject liquid from cylinder 151 through channel 153 and valve casing 164 into drain channel 166, and the movement of piston 150 will be regulated by piston 161 throttling the flow from channel 153. Cam 172 will move with piston 150 and permit follow-up rod 170 to move downward and lower the pivot point of lever 168 so that follow-up rod 170 tends to move pilot valve 160 downward as fast as differential 169 tends to move it upward. Consequently, when the car speed becomes uniform so that pump 10 is delivering liquid to motor 3 at a constant rate, piston 161 will block the end of channel 153 and prevent further adjustment of motor 3.

When the car speed decreases, the rate at which pump 10 delivers liquid to motor 3 will correspondingly decrease and cause motor 3 to tend to decelerate but, as soon as motor 3 tends to decelerate, it will rotate shaft 169^b through a lesser angular distance than shaft 169^c is being rotated by motor 177, thereby causing differential case 169^a to rotate a limited angular distance clockwise and to move the right end of lever 168 upward.

Lever 168 will pivot upon follow-up rod 170 and move pilot valve 160 downward to slightly open the end of channel 153 to channel 165 and then liquid from the high pressure side of the circuit will flow through channel 165, valve casing 164 and channel 153 to cylinder 151 and cause piston 150 to move toward the right and effect a reduction in motor displacement corresponding to the reduction in the rate of liquid flow so as to maintain the motor speed substantially constant. Cam 172 will move with piston 150 and raise follow-up rod 170 and the pivot point of lever 168 so that follow-up rod 170 tends to move pilot valve 160 upward as fast as differential 169 tends to move it downward. Consequently, if the car speed again becomes uniform so that pump 10 is delivering liquid to motor 3 at a constant rate, piston 161 will block the end of channel 153 and prevent further adjustment of motor 3. If the car speed continues to decrease, differential 169 will continue to effect reduction of motor displacement and thereby maintain motor speed substantially constant until the car speed drops below the predetermined intermediate speed and then the car lighting and air conditioning apparatus will be driven by the D. C. motor-generator.

Motor 3 thus operates at a substantially constant speed during operation of the car at all speeds above a predetermined intermediate speed such as 25 M. P. H., and it preferably is of such capacity that its displacement is less than maximum when the car reaches its maximum cruising speed, such as 100 M. P. H., so that its speed may be maintained substantially constant until the car reaches a peak speed such as 120 M. P. H.

Instead of employing a variable displacement

hydraulic motor and varying the displacements of both the pump and the motor to maintain the motor speed substantially constant, a constant displacement motor may be employed and its speed maintained nearly constant by varying pump displacement inversely to variations in pump speed as previously explained.

If it is desired to maintain the speed of a constant displacement motor more nearly constant than is practical by varying the displacement of the pump, pump displacement may be varied inversely to variations in pump speed to cause the pump to deliver liquid to the motor at a substantially constant rate, and a small percentage of the motive liquid may be bypassed around the motor under the control of a bypass valve which is shifted to vary the flow of bypassed liquid in response to the motor speed tending to vary from a predetermined constant.

This could readily be accomplished by using the speed responsive mechanism shown in Fig. 3 as it would only be necessary to substitute a bypass valve for pilot valve 160 and to cause follow-up rod 170 to move in response to movement of the valve. Since such a construction is obvious from the foregoing description, it has not been illustrated.

The invention herein set forth is susceptible of various modifications and adaptations without departing from the scope thereof. The invention is hereby claimed as follows:

1. In a hydraulic drive, the combination of a variable displacement pump adapted to be driven at varying speeds, a variable displacement hydraulic motor, fluid channels connecting said pump and said motor to each other and forming therewith a hydraulic circuit, means for varying the displacement of said pump in response to variations in the speed thereof, and means responsive to the speed of said motor varying from a predetermined speed for varying the displacement of said motor to thereby maintain said predetermined motor speed substantially constant during operation of said pump at speeds above a predetermined minimum speed.

2. In a hydraulic drive, the combination of a variable displacement pump adapted to be driven at varying speeds, a variable displacement hydraulic motor, fluid channels connecting said pump and said motor to each other and forming therewith a hydraulic circuit, means for varying the displacement of said pump in response to variations in the speed thereof, means for varying the displacement of said motor between a minimum and a maximum, hydraulic means for operating said motor displacement varying means, a pilot valve for controlling said hydraulic means, and means responsive to the speed of said motor varying from a predetermined speed for operating said pilot valve.

3. In a hydraulic drive, the combination of a variable displacement pump adapted to be driven at varying speeds, a variable displacement hydraulic motor, fluid channels connecting said pump and said motor to each other and forming therewith a hydraulic circuit, means for varying the displacement of said pump in response to variations in the speed thereof, means for varying the displacement of said motor between a minimum and a maximum, hydraulic means for operating said motor displacement varying means, a pilot valve for controlling said hydraulic means, a differential having one leg driven by said motor and a second leg driven at a substantially constant speed so that a variation in motor speed

relative to said constant speed causes movement of the third leg of said differential, and means for operating said pilot valve in response to movement of said third leg.

5. In a hydraulic drive, the combination of a variable displacement pump adapted to be driven at varying speeds, a variable displacement hydraulic motor, fluid channels connecting said pump and said motor to each other and forming therewith a hydraulic circuit, means for varying the displacement of said pump in response to variations in the speed thereof, means for varying the displacement of said motor between a minimum and a maximum, hydraulic means for operating said motor displacement varying means, a pilot valve for controlling said hydraulic means, a differential having one leg driven by said motor and a second leg driven at a substantially constant speed so that a variation in motor speed relative to said constant speed causes movement of the third leg of said differential, means responsive to movement of said third leg for shifting said pilot valve in one direction or the other from a neutral position to cause said hydraulic means to operate said motor displacement varying means, and means responsive to operation of said hydraulic means for returning said pilot valve to its neutral position.

5. In a hydraulic drive, the combination of a reversible variable displacement pump adapted to be driven in one direction or the other, a hydraulic motor, fluid channels connecting said pump and said motor to each other and forming therewith a hydraulic circuit, and means for reversing said pump in response to a change in the direction in which said pump is driven to thereby cause said pump to deliver liquid to one side only of said motor and said motor to operate in only one direction regardless of the direction in which said pump is driven.

6. In a hydraulic drive, the combination of a reversible variable displacement pump adapted to be driven in one direction or the other, a hydraulic motor, fluid channels connecting said pump and said motor to each other and forming therewith a hydraulic circuit, means for reversing said pump in response to a change in the direction in which said pump is driven to thereby cause said pump to deliver liquid to one side only of said motor and said motor to operate in only one direction regardless of the direction in which said pump is driven, and means for thereafter varying the displacement of said pump inversely to variations in pump speed to thereby avoid corresponding variations in the speed of said motor.

7. In a hydraulic drive, the combination of a reversible variable displacement pump adapted to be driven in one direction or the other, a hydraulic motor, fluid channels connecting said pump and said motor to each other and forming therewith a hydraulic circuit, means tending to adjust said pump to zero displacement, and means responsive to said pump being driven in one direction or the other for adjusting said pump to cause it to discharge in the same direction and said motor to operate in only one direction regardless of the direction in which said pump is driven.

8. In a hydraulic drive, the combination of a reversible variable displacement pump adapted to be driven in one direction or the other, a hydraulic motor, fluid channels connecting said pump and said motor to each other and forming therewith a hydraulic circuit, means tending to adjust said pump to zero displacement, means responsive to said pump being driven in one direc-

tion or the other for adjusting said pump to cause it to discharge in the same direction and said motor to operate in only one direction regardless of the direction in which said pump is driven, and means for thereafter varying the displacement of said pump inversely to variations in pump speed to thereby avoid corresponding variations in the speed of said motor.

9. In a hydraulic drive, the combination of a reversible variable displacement pump adapted to be driven in one direction or the other, a hydraulic motor, fluid channels connecting said pump and said motor to each other and forming therewith a hydraulic circuit, means for reversing said pump in response to a change in the direction in which said pump is driven to thereby cause said pump to deliver liquid to one side only of said motor and said motor to operate in only one direction regardless of the direction in which said pump is driven, and means operable only after the speed of said pump has reached a given value for varying pump displacement inversely to variations in pump speed above that value to thereby avoid corresponding variations in the speed of said motor.

10. In a hydraulic drive, the combination of a reversible variable displacement pump adapted to be driven in one direction or the other, a hydraulic motor, fluid channels connecting said pump and said motor to each other and forming therewith a hydraulic circuit, means tending to adjust said pump to zero displacement, means responsive to said pump being driven in one direction or the other for adjusting said pump to cause it to discharge in the same direction and said motor to operate in only one direction regardless of the direction in which said pump is driven, and means operable only after the speed of said pump has reached a given value for varying pump displacement inversely to variations in pump speed above that value to thereby avoid corresponding variations in the speed of said motor.

11. In a hydraulic drive, the combination of a main pump adapted to be driven at varying speeds, a hydraulic motor, fluid channels connecting said pump and said motor to each other and forming therewith a hydraulic circuit, means for varying the displacement of said main pump, an auxiliary pump driven in unison with said main pump, hydraulic means operated by liquid supplied thereto by said auxiliary pump for moving said displacement varying means toward maximum displacement position, and hydraulic means responsive to the velocity of the liquid supplied by said auxiliary pump exceeding a predetermined rate for moving said displacement varying means away from its maximum displacement position to thereby prevent an increase in the speed of said main pump above a predetermined speed from causing a corresponding increase in the speed of said motor.

12. In a hydraulic drive, the combination of a main pump adapted to be driven at varying speeds, a hydraulic motor, fluid channels connecting said pump and said motor to each other and forming therewith a hydraulic circuit, means for varying the displacement of said main pump, means normally urging said displacement varying means to neutral position, an auxiliary pump driven in unison with said main pump, hydraulic means operated by liquid supplied thereto by said auxiliary pump for moving said displacement varying means toward maximum displacement position, and hydraulic means responsive to the

velocity of the liquid supplied by said auxiliary pump exceeding a predetermined rate for moving said displacement varying means away from its maximum displacement position to thereby prevent an increase in the speed of said main pump above a predetermined speed from causing a corresponding increase in the speed of said motor.

13. In a hydraulic drive, the combination of a main pump adapted to be driven at varying speeds, a hydraulic motor, fluid channels connecting said pump and said motor to each other and forming therewith a hydraulic circuit, means for varying the displacement of said main pump, a first hydraulic actuator, a second hydraulic actuator, a floating lever pivoted to both of said actuators and connected to said displacement varying means, an auxiliary pump driven in unison with said main pump and adapted to deliver liquid to said first actuator and cause it to move said lever in a direction to effect movement of said displacement varying means toward maximum displacement position, means responsive to movement of said first actuator for directing liquid from said auxiliary pump to said second actuator, and means responsive to the velocity of the liquid delivered by said auxiliary pump exceeding a predetermined rate for causing said second actuator to move said lever in the opposite direction and thereby effect movement of said displacement varying means away from its maximum displacement position so as to prevent an increase in the speed of said main pump above a predetermined speed from causing a corresponding increase in the speed of said motor.

14. In a hydraulic drive, the combination of a main pump adapted to be driven at varying speeds, a hydraulic motor, fluid channels connecting said pump and said motor to each other and forming therewith a hydraulic circuit, means for varying the displacement of said main pump, a first hydraulic actuator, a second hydraulic actuator, a floating lever pivoted to both of said actuators and connected to said displacement varying means, spring means normally urging said actuators to such positions that said lever holds said displacement varying means in its neutral position, an auxiliary pump driven in unison with said main pump and adapted to deliver liquid to said first actuator and cause it to move said lever in a direction to effect movement of said displacement varying means toward maximum displacement position, means responsive to movement of said first actuator for directing liquid from said auxiliary pump to said second actuator, and means responsive to the velocity of the liquid delivered by said auxiliary pump exceeding a predetermined rate for causing said second actuator to move said lever in the opposite direction and thereby effect movement of said displacement varying means away from its maximum displacement position so as to prevent an increase in the speed of said main pump above a predetermined speed from causing a corresponding increase in the speed of said motor.

15. In a hydraulic drive, the combination of a main pump adapted to be driven in one direction or the other and provided with displacement varying means movable selectively in opposite directions from a neutral position, a hydraulic motor, fluid channels connecting said pump and said motor to each other and forming therewith a hydraulic circuit, an auxiliary pump driven in one direction or the other in unison with said main pump and adapted to

70

deliver liquid in one direction or the other, and hydraulic means energized by said auxiliary pump and adapted to move said displacement varying means in one direction or the other in accordance with the direction of delivery of said auxiliary pump to thereby cause said main pump to discharge in a given direction and said motor to operate in only one direction regardless of the direction in which said main pump is driven.

16. In a hydraulic drive, the combination of a main pump adapted to be driven in one direction or the other at varying speeds and provided with displacement varying means movable selectively in opposite directions from a neutral position, a hydraulic motor, fluid channels connecting said pump and said motor to each other and forming therewith a hydraulic circuit, an auxiliary pump driven in one direction or the other in unison with said main pump and adapted to deliver liquid in one direction or the other, hydraulic means energized by said auxiliary pump and adapted to move said displacement varying means in one direction or the other in accordance with the direction of delivery of said auxiliary pump to thereby cause said main pump to discharge in a given direction and said motor to operate in only one direction regardless of the direction in which said main pump is driven, and means operable only after the speed of said main pump has reached a given value for causing said hydraulic means to vary pump displacement inversely to variations in pump speed above that value to thereby avoid corresponding variations in the speed of said motor.

17. In a hydraulic drive, the combination of a main pump adapted to be driven in one direction or the other at varying speeds and provided with displacement varying means movable selectively in opposite directions from a neutral position, a hydraulic motor, fluid channels connecting said pump and said motor to each other and forming therewith a hydraulic circuit, a first hydraulic actuator, a second hydraulic actuator, means connecting both of said actuators to said displacement varying means so that operation of one or the other of said actuators will cause said displacement varying means to be moved in one direction or the other, an auxiliary pump driven in one direction or the other in unison with said main pump and adapted to deliver liquid in one direction or the other, and means responsive to said auxiliary pump delivering liquid in one direction or the other for directing liquid from said auxiliary pump to that one of said actuators which will effect movement of said displacement varying means in a direction to cause said main pump to discharge in a given direction and said motor to operate in only one direction regardless of the direction in which said main pump is driven.

18. In a hydraulic drive, the combination of a main pump adapted to be driven in one direction or the other at varying speeds and provided with displacement varying means movable selectively in opposite directions from a neutral position, a hydraulic motor, fluid channels connecting said pump and said motor to each other and forming therewith a hydraulic circuit, a first hydraulic actuator, a second hydraulic actuator, means connecting both of said actuators to said displacement varying means so that operation of one or the other of said actuators will cause said displacement varying means to be

moved in one direction or the other, an auxiliary pump driven in one direction or the other in unison with said main pump and adapted to deliver liquid in one direction or the other, means responsive to said auxiliary pump delivering liquid in one direction or the other for directing liquid from said auxiliary pump to that one of said actuators which will effect movement of said displacement varying means in a direction to cause said main pump to discharge in a given direction and said motor to operate in only one direction regardless of the direction in which said main pump is driven, and means responsive to the velocity of the liquid delivered by said auxiliary pump exceeding a predetermined rate for causing said second actuator to effect movement of said displacement varying means in the opposite direction so as to prevent an increase in the speed of said main pump above a predetermined speed from causing a corresponding increase in the speed of said motor.

19. In a hydraulic drive, the combination of a pump adapted to be driven in one direction or the other and having displacement varying means operable to reverse the direction of pump delivery in respect to the direction in which said pump is driven and also to vary the rate of pump delivery, a hydraulic motor, fluid channels connecting said pump to said motor and forming therewith a hydraulic circuit, and means responsive to a change in the direction in which said pump is driven for effecting operation of said displacement varying means to cause said pump to deliver liquid to one side only of said motor so that said motor operates in one direction only regardless of the direction in which said pump is driven.

20. In a hydraulic drive, the combination of a pump adapted to be driven in one direction or the other and having displacement varying means operable to reverse the direction of pump delivery in respect to the direction in which said pump is driven and also to vary the rate of pump delivery, a hydraulic motor, fluid channels connecting said pump to said motor and forming therewith a hydraulic circuit, means responsive to a change in the direction in which said pump is driven for effecting operation of said displacement varying means to cause said pump to deliver liquid to one side only of said motor so that said motor operates in one direction only regardless of the direction in which said pump is driven, and means responsive to variations in pump speed for effecting operation of said displacement varying means to vary pump displacement inversely to variations in pump speed and thereby avoid corresponding variations in the speed of said motor.

WALTER FERRIS.
